(57) **CLAIM**

The ornamental design for an electric spin scrubber, as shown and described.

DESCRIPTION

FIG. 1 is a top perspective view of an electric spin scrubber, showing my new design;

FIG. 2 is a bottom perspective view thereof;

FIG. 3 is a top perspective view showing the electric spin scrubber as it would appear when used;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is an enlarged detail view of area 10 in FIG. 1; and, FIG. 11 is an enlarged detail view of area 11 in FIG. 2.

The dash-dash-style broken lines in the drawings illustrate the portions of the electric spin scrubber, which form no part of the claimed design. The dot-dash-style broken lines illustrate the bounds of the enlarged areas taken from FIGS. 1 and 2, as well as the original areas of FIGS. 1 and 2 from which the enlargements were extracted. The boundaries form no part of the claimed design.
